UNITED STATES PATENT OFFICE.

EUGENE S. CRULL, OF DAVENPORT, IOWA, ASSIGNOR TO THE ADJUSTABLE SASII WEIGHT CO., OF SAME PLACE.

WEIGHT.

SPECIFICATION forming part of Letters Patent No. 653,987, dated July 17, 1900.

Application filed March 9, 1900. Serial No. 8,049. (No model.)

To all whom it may concern:

Be it known that I, EUGENE S. CRULL, a citizen of the United States, and a resident of Davenport, in the county of Scott and State 5 of Iowa, have invented a new and Improved Weight, of which the following is a full, clear, and exact description.

The purpose of this invention is to provide a weight, particularly a sash-weight, constructed in a plurality of sections which may be readily joined together so as to hold the weight on a cord or the like, thus facilitating adjusting the weight on the sash with the proper degree of nicety.

15 This specification is the disclosure of one form of my invention, while the claims define the actual scope thereof.

Reference is to be had to the accompanying drawings, forming a part of this specification, 20 in which similar characters of reference indicate corresponding parts in all the views.

Figure 1 is a perspective view of the invention used as a sash-weight. Fig. 2 is a perspective view of the duplicate sections forming the weight, showing them in position to be engaged with each other. Fig. 3 is a sectional view on the line 3 3 of Fig. 4, showing the two sections of the weight joined together; and Fig. 4 is a side elevation of one of the 30 sections of the weight with a part cut away on the line 4 4 of Fig. 2.

Referring to Fig. 1, a number of weights A are mounted on the sash-cord B, one weight above the other, as shown. It will be seen 35 that the number of the weights A may be increased or decreased at will to regulate the amount of stress put on the sash-cord. When the proper number of weights has been applied to the sash-cord, the weights may be held 40 securely by a pin C, driven through the cord B and engaging the uppermost weight A, as shown. Each of the weights A (shown in Fig. 1) comprises two duplicate sections adapted to fit together to form a cylindrical object. Each 45 section of the weight has a longitudinally-disposed main branch a of segmental cross-section and of a size equal to less than one-half of the circumference of the weight. The branch a forms a continuation of the main 50 part b of the section, which is of a size greater than one-half of the cross-sectional form of the weight A and is cut away longitudinally,

so that the main branch a of the other section of the weight may be fitted within the body b, as shown. The two parts a and b of each section of the weight are formed with a longitudinal groove c, these grooves matching when the sections are engaged to form a cylindrical passage extending centrally through the weight for the reception of the sash-cord. 55 The body b of each section of the weight is provided at each side of the branch a with flanking or sub branches d, the top walls of each of which flanking or sub branches constitute a double bevel, or, in other words, the 60 upper portions of the branches d are tapered, as shown. At the bases of the branches d of each section of the weight inclined shoulders e are formed, which run into the side walls of the branch a.

Now it will be seen, especially by reference to Fig. 2, that when the two sections of the weight are moved longitudinally toward each other the branches a of the two sections respectively move into the open portions of the 75 bases and the beveled walls of the flanking branches d interengage, as shown, so that the sections cannot be disengaged except by a reversal of the movement which engages them. It may also be seen, especially in connection 80 with Fig. 2, that since the body b of each section of the weight is of a size greater than one-half of the circular form of the weight the groove c therein is of an extent greater than that of a semicircle. This groove describes 85 approximately two-thirds of a circle, and when a knot (B' in Fig. 1) is formed in the sash-cord this knot engages the body portion b of that section of the weight which has its body portion downward. This prevents the knot from 90 slipping into the groove c and lifting the other section of the weight. Therefore the weight is supported by the engagement of the knot on the cord with the body portion b of that section of the weight which has the body portion downward, and such section of the weight 95 serves in turn to support the other section, owing to the interengagement of the flanking branches d of the several sections, as described.

100 The advantage of this weight is that it may be applied to the cord at any point intermediate its ends and that it is not necessary to string the cord longitudinally through the

passage in the weight. One weight may be placed in position on top of another without disturbing the first weight, and thus it will be seen that the weights may be applied to or disposed from the cord with the utmost facility. Further, this invention enables merchants to carry in stock a uniform or standard article, which may be used on different sashes, and avoids the inconvenience heretofore experienced, which is that merchants are required to carry in stock a large number of sash-weights of different sizes with which to accommodate the various demands of the trade.

Having thus described my invention, I claim as new and desire to secure by Letters Patent—

1. A weight formed of two duplicate sections, each of which comprises a body with a main branch thereon, the main branch of one section being adapted to fit into an opening in the body of the other section, and the sections also having interengaging branches flanking the main branches.

2. A weight formed of two duplicate sections, each of which comprises a body portion with an open portion, and a branch, the branches respectively fitting in the open portions of the bodies, each section also comprising beveled flanking branches which interen-

gage to sustain one section on the other, and the sections having grooves which match to form a passage extending through the weight.

3. A weight for sash-cords and the like, the weight being formed in two duplicate sections, each having a body with an opening in the side thereof, a main branch extending from the body, the main branches respectively lying in the said openings, and each weight-section also having one or more flanking or sub branches which interengage to sustain one section on the other.

4. A weight for sash-cords and the like, the weight being formed in two duplicate sections, each section comprising a body with an opening in the side thereof, a main branch on each weight-section, the branches respectively lying in the open portions of the bodies of the weight-sections, and interengaging means formed on the weight-sections for sustaining one on the other.

In testimony whereof I have signed my name to this specification in the presence of two subscribing witnesses.

EUGENE S. CRULL.
